Primary Examiner — Catheri Oliver-Garcia*Assistant Examiner* — Rebekah Caruso(74) *Attorney, Agent, or Firm* — Proskauer Rose LLP(57) **CLAIM**

The ornamental design for a non-invasive neurostimulation device, substantially as shown.

DESCRIPTION

FIG. 1 is a perspective view of a non-invasive neurostimulation device incorporating the design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines shown in the drawings illustrate portions of the non-invasive neurostimulation device that form no part of the claimed design.

1 Claim, 5 Drawing Sheets(56)
